UNITED STATES PATENT OFFICE

FRITZ JAHN, OF BERLIN-PANKOW, GERMANY, ASSIGNOR TO GENERAL ELECTRIC COMPANY, A CORPORATION OF NEW YORK

ELECTRICAL REGULATOR

Application filed October 24, 1930, Serial No. 490,960, and in Germany December 27, 1929.

This invention relates to electrical regulators, and more particularly to automatic carbon pile regulators.

Automatic solenoid operated carbon pile regulators are well known in the art. In the past such regulators have never been entirely satisfactory because the peculiar characteristics of carbon piles, which militate against their direct actuation by the ordinary regulator operating element which responds to the condition to be regulated, have been compensated for, if at all, by relatively complicated apparatus.

The first characteristic of carbon piles which leads to complications is the fact that their resistance decreases with increases in pressure applied to them. Now, as in practically all automatic regulators, an increase in the value of the regulated quantity is accompanied by an increase in the force produced by the element, usually a solenoid, connected to be responsive to the quantity, a direct application of the force to the pile will result in a decrease in resistance; whereas, an increase in resistance is what is usually needed. Thus, if the regulator is a voltage regulator, an increase in voltage should be accompanied by an increase in resistance, regardless of whether the resistance is in the circuit whose voltage is to be regulated, or whether it is in the field circuit of a generator. To overcome this difficulty prior carbon pile regulators have been provided with means, such as weights or springs, which normally keep the pile compressed, the actuating element being connected to decrease the pressure on the pile with increases in the value of the regulated quantity. Such additional means increases the number of moving parts of the regulator and also increases the friction in it, with the result that its speed and sensitivity of response are impaired.

The second characteristic of carbon piles which leads to difficulties when they are used in automatic regulators, is the fact that their change of resistance is not a simple straight line function of the compressing pressure. In fact, their resistance-pressure characteristic resembles an hyperbola, the resistance, as ordinates, being a maximum at zero pres-

sure, and falling away rapidly at first and then more and more slowly as the pressure, as abscissæ, increases to a maximum. Now the well-known force-displacement or pull characteristics of the ordinary solenoid, which is what has heretofore been generally used as the actuating element of a carbon pile regulator, is about as far on the other side of a straight line as is the pressure-resistance characteristic of a carbon pile. Such a pull characteristic, with pull as ordinates against displacement of the core from the mid position, as abscissæ, resembles a quarter section of an ellipse whose center is at the origin of coordinates, and whose major axis is along the horizontal of coordinates. In other words, the pull decreases gradually at first, and then more rapidly as the displacement increases. The result is that when a carbon pile is actuated by the core of an ordinary solenoid, without the interposition of special connecting means, a very erratic action, which also is accompanied by considerable hunting, is the usual consequence, because given changes in the energization of the solenoid will not produce directly proportional changes in the value of the resistance of the pile. Various attempts to solve this difficulty have been made in the past, such as using specially designed solenoid cores, or interposing special mechanical connections between the solenoid core and the pile, as for example, special lever systems or systems utilizing the hyperbolic pressure-volume characteristic of a gas. However, these arrangements are complicated, expensive and increase the friction in the regulator thus tending to decrease its sensitivity and speed of action. Furthermore, most of these arrangements seem to assume that the pull characteristic of a solenoid is a straight line.

In accordance with this invention there is provided a novel electromagnetic operating means for carbon pile regulators, which, with a minimum number of moving parts, provides an operating characteristic suitable for operation of a carbon pile, and which may be directly electrically connected to the circuit to be regulated, and which may be directly mechanically connected to the carbon pile.

- An object of the invention is to provide a new and improved electrical regulator. Another object of the invention is to provide a simplified electromagnetic actuating element for electrical regulators which is particularly adapted for use in carbon pile regulators, or any regulator with a compressible resistance medium having an exponential or non-linear resistance pressure characteristic.
- 10 The invention will be better understood from the following description taken in connection with the accompanying drawings, and its scope will be pointed out in the appended claims.
- 15 In the drawings, in which like characters of reference refer to similar elements throughout the several figures, Fig. 1 illustrates one arrangement of the operating windings of the magnet whereby increases in the regulated quantity results in a decrease in the net ampere turns of the magnet; Fig. 2 is a modification of the arrangement shown in Fig. 1; Fig. 3 illustrates the operating characteristics of a carbon pile resistance; Fig. 4 illustrates pictorially the significance of the coordinates used in Fig. 3; Fig. 5 is a front elevation of the core and armature of the operating magnet; Fig. 6 is a side elevation thereof; Fig. 7 shows graphically the operating characteristic of the operating magnet; Fig. 8 is a modified arrangement of connections of a carbon pile whereby an increased current-carrying capacity is obtained; Fig. 9 is a side elevation of the completed regulator embodying the invention; while Fig. 10 is a front view thereof.
- In Fig. 1, 1 is an electric circuit, one of whose electrical quantities, in this case voltage, is to be regulated by the regulator.
- 40 Across this circuit are connected coils 2 and 3, coil 3 having in series therewith a constant current device 4. This constant current device may be of any well-known construction, such as the well-known iron wire ballast lamp. Coils 2 and 3 are so connected that their magnetomotive forces oppose each other, the ampere turns of the coil 3 at normal voltage on circuit 1 being greater than the ampere current of coil 2. With this arrangement an increased voltage on circuit 1 will increase the current through coil 2, and therefore its ampere-turns, but due to the well-known action of constant current device 4, which has a high temperature coefficient of resistance, the increase in voltage on circuit 1 will all be absorbed by an increase in voltage drop across resistance 4, so that the ampere-turns of coil 3 will remain practically constant throughout a considerable range of voltage change on circuit 1. The result will be that, as the magnetomotive forces of the coils are opposite, an increase in voltage will result in a net decrease in the total ampere turns of both coils. Therefore
- 45 the armature of such a magnet which is con-

nected directly to a carbon pile, will cause a decrease in pressure on it, and hence an increase in the resistance of the pile with increases in voltage applied to the operating winding of the magnet. In a similar manner, decreases in the voltage applied to the operating magnet will result in a decrease in the resistance of the carbon pile.

50 In addition to the fact that an operating magnet having coils arranged as shown in Fig. 1 will cause a decrease in operating force with increase in voltage, this arrangement has another advantage in that the effective number of ampere turns of the magnet, and hence the force produced by the magnet varies at a greater rate than the voltage applied to the coil. For example, if at normal voltage the number of ampere turns of the constant current coil is 1000, and the number of ampere turns of the variable current coil is 80, the net number of ampere turns available for producing a force on the armature is 100. If now the exciting voltage increase by 1%, the number of ampere-turns of the variable current coil increases to 909, while the effective number of ampere-turns of the entire system falls from 100 to 91. Therefore, a change of the net ampere-turns of the two coils of 9% corresponds to a change of voltage of 1%. This corresponds to a variation of the attractive force of the magnet of about 20%. It will thus be seen that a regulator employing an operating magnet arranged as in Fig. 1, will be much more sensitive than an ordinary regulator whose operating magnet has but a single coil.

55 In the modification shown in Fig. 2, the same effect, but to a greater degree, is obtained. In this figure variable current coil 2 is connected across the ballast resistor 4 instead of directly across the circuit 1, constant current coil 3 being connected in series with the ballast resistor 4.

If rapid movement of the armature of the operating magnet, caused by a great variation in the attractive force of the magnet with slight voltage variations is not desirable, its motion can be damped, by arranging short-circuited turns on the core of the operating magnet or on the armature.

60 In order to obtain the simplest possible mechanical construction of the regulator, it is desirable that the movable element of the operating magnet press without intermediate members as directly as possible on the carbon pile. This is made possible, according to another feature of the invention, by giving the magnet the same characteristics as those for the carbon pile. This is obtained as follows:

65 In Fig. 4, 5 represents a carbon pile. L minimum represents the length of this pile when fully compressed, and L maximum represents the uncompressed length of this pile. P represents the compressing pressure, and

d represents the difference between the actual length and the fully compressed length of the pile. Fig. 3 illustrates graphically the relation between *P* and *d*. As changes in *d* are proportional to changes in the resistance of the pile, the curve illustrated in Fig. 3 is also illustrative of the pressure-resistance characteristic of the carbon pile.

In order to obtain best results with the movable element of the operating magnet connected directly to press upon the carbon pile, it is necessary that the operating magnet have a characteristic which is similar to the characteristic of the carbon pile illustrated in Fig. 3. An operating magnet having this characteristic is illustrated in Figs. 5 and 6, where 6 is the stationary core upon which the operating coils are wound, 7 is the armature which is pivotally mounted at 8, and 9 are small non-magnetic pieces set in the poles of the stationary element 6 for preventing freezing of the armature to the core. *P* represents the force by which the armature is attracted to the core 6, while *d* represents the displacement of the armature from the poles of the core 6. The operating characteristics of such a magnet are illustrated in Fig. 7 with *P* the attractive force as ordinates and *d* the displacement of the armature as abscissæ.

As will be seen the shape of this curve is very similar to the operating characteristics of the carbon pile illustrated in Fig. 3. The fact that the lower part of this curve does not intersect the horizontal axis, but is asymptotic to it, is immaterial from a practical standpoint. The special construction of the operating magnet illustrated in Figs. 5 and 6, which gives this operating characteristic, resides in the fact that the length of the air gap is small in comparison with its active cross-section.

As any given carbon pile is only capable of carrying safely a certain maximum current, there is illustrated in Fig. 8 an arrangement whereby this maximum current may be doubled for any pile. As shown, the pile is divided into three sections, 10, 11 and 12, the middle section being half the total length of the pile, while the end sections 10 and 12 are respectively one-fourth the total length of the pile. Conducting elements 13 and 14 serve to separate the sections of the pile, while conducting elements 15 and 16 are mounted at the ends of the pile. Conducting sections 15 and 16 are connected by conductor 17, while intermediate conducting sections 13 and 14 are connected to conductors 18 and 19, which may be connected in any suitable regulating circuit. It will be seen from this arrangement that the current through the pile has two paths, one being through the middle section 11 and the other being through end sections 10 and 12 in series. In this manner the current carrying capacity of the pile is doubled.

Although the invention has only been shown and described in connection with a carbon pile regulator it will be readily apparent to those skilled in the art that the invention is not so limited and that it is suitable for use with any compressible resistance medium having characteristics similar to those of a carbon pile.

Figs. 9 and 10 illustrate the completed regulator embodying the above-described features of the invention. In these figures 24 is a base upon which a bracket 25 is fastened by any suitable means. Supported by this bracket is the carbon pile 5. This bracket also supports through a pivotal connection 8, the armature 7 of the operating magnet. A counterbalance 20 is provided for the armature in order to relieve the pressure on the pile, due to the weight of the armature, when the operating magnet is fully energized. As shown, the carbon pile is hollow and has passing through it a rod 21, which connects at its lower end to the armature 7, and at its upper end to the upper end of the carbon pile 5 by means of a nut 22, whereby an adjustment of the setting may be secured. Bracket 25 also carries an adjustable stop 23. A suitable supporting bracket 26 serves to fasten the core 6 of the operating magnet to the base 24.

It will now be seen that there have been shown and described a novel carbon pile voltage regulator in which the movable element of the operating magnet is connected directly to the carbon pile, the pressure-displacement characteristic of the operating magnet being similar in shape to the pressure-displacement or pressure-resistance characteristic of the carbon pile, while at the same time the force produced by the operating magnet decreases with increases in the magnitude of the regulated quantity, so that with such increases the resistance of the carbon pile will also increase.

While there have been shown and described particular embodiments of the invention, it will be obvious to those skilled in the art that changes and modifications may be made without departing from the invention, and it is therefore intended in the appended claims to cover all such changes and modifications as fall within the true spirit and scope of the invention.

What I claim as new and desire to secure by Letters Patent of the United States is:

1. An electrical regulator having an operating magnet for a compressible pile including two differentially related coils, one of which normally produces a greater number of ampere-turns than the other, and a constant current device associated with the coil normally producing the greatest number of ampere-turns.

2. In a regulating system for the voltage of an electric circuit, a compressible pile regu-

- lator having an operating magnet comprising a pair of differentially acting coils connected to be responsive to the voltage of said circuit, a constant current device associated with one of said coils for maintaining constant current in said coil regardless of the voltage of said circuit, said coil producing a greater number of ampere turns than the other at normal voltage, whereby the rate of change of net ampere-turns in said magnet in response to changes in the voltage of said circuit, is greater than the rate of change of voltage of said circuit.
3. An operating magnet for an electrical regulator having two parallel connected differentially acting coils, and a constant current device in series with one of said coils.
4. An operating magnet for an electrical regulator having two parallel connected differentially acting coils, one of which is connected in series with a constant current device, said coil being adapted to normally produce a greater number of ampere turns than the other.
5. An operating magnet for a compressible pile electrical regulator having two series connected differentially acting coils, one of which is in parallel with a constant current device.
6. An operating magnet for a compressible pile electrical regulator having two series connected differentially acting coils, one of which is in parallel with a constant current device, and the other of which normally produces the greater number of ampere turns.
7. In combination, an electric circuit having a normal voltage, an operating magnet for a carbon pile voltage regulator including a pair of coils connected across said circuit, and a constant current device associated with one of said coils in a manner to maintain the current therein substantially constant during voltage variations on said circuit, said coils being differentially related with respect to a common magnetic circuit, the constant current coil being adapted to produce the greatest number of ampere turns at normal voltage.
8. In combination, an electric circuit having a normal voltage, an operating magnet for carbon pile voltage regulator including a pair of coils connected in parallel across said circuit, and a constant current device associated with one of said coils in a manner to maintain the current therein substantially constant during voltage variations on said circuit, said coils being differentially related with respect to a common magnetic circuit, the constant current coil being adapted to produce the greatest number of ampere turns at normal voltage.
9. In combination, an electric circuit having a normal voltage, an operating magnet for a carbon pile voltage regulator including a pair of coils connected in series across said circuit, and a constant current device asso-
- ciated with one of said coils in a manner to maintain the current therein substantially constant during voltage variations on said circuit, said coils being differentially related with respect to a common magnetic circuit, the constant current coil being adapted to produce the greatest number of ampere turns at normal voltage.
10. An electrical regulator comprising a compressible resistance element having a pressure-resistance characteristic substantially hyperbolic in shape, and a compressing electromagnet for said resistance element, said electromagnet having a core and cooperating armature, the air gap between which is short with respect to its cross-section whereby the force-displacement characteristic of said electromagnet is substantially the same as the pressure-resistance characteristic of said resistance element.
11. In combination, a carbon pile, an electromagnet, a core for said electromagnet, said core having a pole, a movably mounted armature adjacent to said pole, the air gap between said pole and said armature being short in comparison with its cross-section, and means connecting said armature to said carbon pile in such a manner that the movements of said armature toward said pole result in a directly proportional motion of one end of said pile toward its other end.
12. An electrical regulator, having in combination, a resistance element whose electrical resistance varies inversely with the compressing pressure applied to it, an electromagnetic device having a core and an armature, said device producing an attractive force between its core and armature which varies inversely with its energization, and means for applying this force directly to said resistance element as a compressing pressure.
13. An electrical regulator comprising, a carbon pile resistance, an electromagnet having a magnetic core and a movable magnetic armature, the electromagnetic attraction between said core and armature varying with the distance between them in substantially the same way that the force required to compress the carbon pile varies with its degree of compression, means directly connecting said armature to said core so that movements of said armature toward its cooperating core cause a directly proportional compression of said pile, and energizing means for said electromagnet which decreases its net ampere turns with increases in the voltage applied to it.
14. An electrical regulator having in combination a carbon pile, a support for one end of said pile, an armature of magnetic material, a core of magnetic material adapted to attract said armature when said core is energized, connecting means between said armature and the unsupported end of said carbon pile for causing the attractive force

on said armature to be applied directly to compressing said pile, a pair of coils wound on said core, said coils being differentially related, one of said coils normally producing
5 a greater number of ampere turns than the other, and a constant current device associated with said first-mentioned coil.

In witness whereof I have hereunto set my hand this 12th day of September, 1930.

FRITZ JAHN.
